DESIGN FOR A COMBINED HOLDER FOR SMOKERS' ARTICLES AND MEMORAN- DUM ACCESSORIES

James Edward Newton, Little Compton, R. I.

Application October 15, 1943, Serial No. 111,371

Term of patent 14 years

(Cl. D85—2)

To all whom it may concern:

Be it known that I, James Edward Newton, a citizen of the United States, residing at Little Compton, in the county of Newport and State of Rhode Island, have invented a new, original, and ornamental Design for Combined Holder for Smokers' Articles and Memorandum Accessories, of which the following is a specification, reference being had to the accompanying drawing, forming a part thereof.

I claim:

The ornamental design for a combined holder for smokers' articles and memorandum accessories as shown.

JAMES EDWARD NEWTON.
